DESIGN FOR A MICROSCOPE

Gustave Fassin, Irondequoit, N. Y., assignor to
Bausch & Lomb Optical Company, Rochester,
N. Y., a corporation of New York

Application April 7, 1934, Serial No. 51,349

Term of patent 14 years

To all whom it may concern:

Be it known that I, GUSTAVE FASSIN, a subject of the King of Belgium, and a resident of the town of Irondequoit, county of Monroe and State of New York, have invented a new, original, and ornamental Design for a Microscope, of which the following is a specification, reference being had to the accompanying drawing, forming a part hereof.

Fig. 1 is a side view of a microscope embodying my new design.

Fig. 2 is a rear view thereof.

Fig. 3 is a top plan view thereof.

Fig. 4 is a view taken substantially on line 4—4 of Fig. 1, showing the base of my microscope.

I claim:

The ornamental design for a microscope substantially as shown.

GUSTAVE FASSIN.
